Douglas B. Acker, Westminster, Colo., assignor to Timpte
Bros., Inc., Denver, Colo., a corporation of Colorado

Filed May 22, 1959, Ser. No. 56,032

Term of patent 14 years

(Cl. D14—3)

FIG 1

FIG. 2

FIG. 3

Fig. 1 is a side elevation of a dump body, embodying my new design;

Fig. 2 is a front perspective view of the dump body of Fig. 1, in raised position; and

Fig. 3 is a rear perspective view thereof.

The dotted line showings of portions of a truck are for purposes of illustration only.

The opposite side of the truck body, not shown, is substantially the same in appearance as the side shown.

I claim:

The ornamental design for a dump body for trucks, as shown and described.
